UNITED STATES PATENT OFFICE.

SIDNEY L. MARKHAM, OF JAMESTOWN, NEW YORK.

WINDOW-FRAME.

1,116,828.

Specification of Letters Patent. Patented Nov. 10, 1914.

Application filed October 24, 1913. Serial No. 797,051.

To all whom it may concern:

Be it known that I, SIDNEY L. MARKHAM, a citizen of the United States, residing at the city of Jamestown, in the county of 5 Chautauqua and State of New York, have invented certain new and useful Improvements in Window-Frames, of which the following, taken in connection with the accompanying drawings, is a specification.

10 The invention relates to frames for window sashes and is especially applicable to my resilient window frame construction as shown in Letters Patent No. 1,068,149, of July 22, 1913; and the object of the improvement is to provide a simple and strong window frame construction which has an adjustment strip for quick close fitting the resilient stops to the sash, which strip also covers the opening into the sash box, thereby 15 presenting a continuous smooth surface for the edge of the window sash; and the invention consists in the combination and arrangement of the parts as shown in the specification and the accompanying drawings 20 and pointed out in the claims.

25 In the drawings, Figure 1 is an elevation of the window frame with one side in section to show the arrangement of the different parts at line W W in Fig. 4. Fig. 2 is a 30 sectional view of the window casing and sash at line X X in Fig. 4. Fig. 3 is a sectional view of the window casing at line 35 Y Y in Fig. 1, showing an elevation of the window jamb with the window sash, stops and adjustment strip removed. Fig. 4 is a crosswise sectional view of the window frame and sash at line Z Z in Fig. 1.

Like numerals of reference refer to corresponding parts in the several views.

40 The numeral 10 designates the window jamb which is largely in one piece, and to which the weight box is attached by means of the pieces 11, 12 and 13 which are preferably attached to one another by means of 45 mortise and rabbet joints so that the size or shape of the opening 14 within the weight box is fixed.

An adjustment strip 15 is provided with a lengthwise tongue and groove joint 16 between it and the jamb piece 10. The adjustment strip 15 serves a triple purpose. It is made wider than the projection 17 between the grooves 18 and 19 for the sash stops 20 and 21 to which it is attached so

that the edges of the strip 15 adjacent the 55 sash stops 20 and 21 may be easily cut away in order to fit the space between the sash stops 20 and 21 to receive the window sash 22 thereby insuring a tight joint. The adjusting strip 15 also covers the opening 23 to 60 the weight box 14 and thereby presents a smooth continuous surface for the sash 22 to slide against. The opening 23 may have the piece 24 inserted therein or not just as desired, since the adjustment strip 15 covers 65 the entire opening 23 and is held firmly in line by the tongue and groove joint 16. The opening 23 is preferably made on the lines of the projection 17 and dotted lines extending through the jamb piece 10, as 70 shown in Fig. 4. It is therefore apparent that the adjustment strip 15 performs the triple office of forming a convenient means for fitting the sash 22, also for covering the opening 23, and for providing a smooth 75 continuous sliding surface for the sash 22.

The sash stops 20 and 21 may be resiliently supported by the springs 25 or may extend to the bottom of the grooves 18 and 19 without departing from my invention. 80 A molding 26 may be provided on the outer side of the sash box piece 11 for the trim of the brick in a brick wall or the siding of a wooden frame building. The inner edge of the jamb piece 10 may have the finishing 85 strip 27 with groove 28 therein for the attachment of the inner wood work of the window frame, or the jamb strip 10 may extend up the full thickness thereof, as desired. 90

I claim as new—

1. In a window frame, a jamb piece having lengthwise grooves therein, sash stops in said grooves, and an adjustment strip attached to the projection on said jamb 95 piece between said lengthwise grooves on said jamb piece, said adjustment strip being wider than said projection.

2. In a window frame, a jamb piece having lengthwise grooves therein, sash stops in said grooves, an adjustment strip wider than the projection between said lengthwise grooves in said jamb piece, and a lengthwise tongue and groove joint between said strip and projection. 100

3. In a window frame, a jamb piece having lengthwise grooves therein, sash stops in said grooves, a weight box attached to

said jamb strip, an opening to said weight box lengthwise of a portion of the projection between said grooves in said jamb strip, and an adjustment strip attached lengthwise of 5 said projection between said grooves covering said opening, substantially as and for the purpose specified.

In testimony whereof I have affixed my signature in the presence of two witnesses.

SIDNEY L. MARKHAM.
